UNITED STATES PATENT OFFICE

156,881

LUBRICATOR CABINET

Thomas L. Hand, Cincinnati, Ohio, assignor to Balcrank, Inc., Disney, near Marburg, Cincinnati, Ohio, a corporation of Ohio

Application March 24, 1948, Serial No. 145,323

Term of patent 7 years

(Cl. D52—2)

To all whom it may concern:

Be it known that I, Thomas L. Hand, a citizen of the United States, residing at Cincinnati, in the county of Hamilton and State of Ohio, have invented a new, original, and ornamental Design for a Lubricator Cabinet, of which the following is a specification, reference being had to the accompanying drawing, forming a part thereof.

I claim:

The ornamental design for a lubricator cabinet, substantially as shown.

THOMAS L. HAND.
